UNITED STATES PATENT OFFICE.

THOMAS LEGGETT STURTEVANT, OF QUINCY, AND THOMAS JOSEPH STURTEVANT, OF WELLESLEY, MASSACHUSETTS, ASSIGNORS TO STURTEVANT MILL COMPANY, OF PORTLAND, MAINE, A CORPORATION OF MAINE.

POWER-TRANSMITTING MECHANISM.

SPECIFICATION forming part of Letters Patent No. 794,899, dated July 18, 1905.

Application filed January 4, 1905. Serial No. 239,596.

To all whom it may concern:

Be it known that we, THOMAS LEGGETT STURTEVANT, residing at Quincy, and THOMAS JOSEPH STURTEVANT, residing at Wellesley, in the county of Norfolk and State of Massachusetts, citizens of the United States, have invented certain new and useful Improvements in Power-Transmitting Mechanisms, of which the following is a specification, reference being had therein to the accompanying drawings.

This invention relates to a power-transmitting mechanism by means of which a driven part or shaft may be operated from a driving shaft or motor at different speeds, preferably through the medium of friction-clutch devices; and the invention has for its object to provide means whereby the speed-changing mechanism may be controlled, either automatically or non-automatically or manually, in such a manner that the motor may run at any desired speed without necessarily imparting a high speed of rotation to the driven part or shaft, as also to provide means whereby the load or resistance on the driven part or shaft may exceed a certain predetermined point without necessarily effecting any change in the gearing or power-transmitting mechanism.

The present invention is preferably but not necessarily carried into effect through the medium of fluid-pressure in which air will preferably be the pressure medium, and in thus utilizing fluid-pressure for the purpose of effecting changes from high speed to low speed, or vice versa, a regulation of the fluid-pressure to determine the change of speed may be either automatic or non-automatic or by the combination of the two, as may be deemed preferable.

In the accompanying drawings, Figure 1 is a longitudinal sectional view of a power-transmitting mechanism embodying one form of the present invention, and Fig. 2 is a detail section on line 22, Fig. 1.

Referring to the drawings, 12 denotes the driving-shaft, which may be a part of a mo-

tor-shaft or may be operated in any suitable way from any suitable motor or source of power. The power-shaft 12 is suitably secured, as by screw-bolts 13, to a fly-wheel and clutch-casing 14, within which is inclosed a hub 15, splined to a shaft 16, which latter is the shaft or part to be driven and which may be the operating-shaft of an automobile, or the said shaft 16 may be utilized for any other purpose. Loosely mounted on the shaft 16 is a sleeve 17, integral or rigid with which are the clutch-hub 18 and the pinion 19, said pinion 19 meshing with a gear ring or wheel 20, connected with a hub 21 by a silent ratchet or gripping device, such as is described in our United States Patent No. 766,551, and comprising spring-pressed gripping-rollers 22. The hub 21 is keyed to a counter-shaft 23, mounted in the gear-casing 23^a and provided with a pinion or gear wheel 24, also keyed to said shaft and meshing with a gear-wheel 25, keyed to the driven shaft 16.

Inclosed within the casing or fly-wheel 14 are the low-speed clutch disks or rings 26 and 27, the disks or rings 26 having suitable notched engagements at their peripheries with suitable lugs or projections on the interior of the fly-wheel, and the rings or disks 27 having similar notched engagements with the clutch-hub 18. Also inclosed within the fly-wheel are the high-speed clutch disks or rings 28 and 29, the disks or rings 28 being engaged at their peripheries with the fly-wheel and the disks or rings 29 being engaged at their inner portions with the clutch-hub 15, keyed to the shaft 16. Interposed between the high-speed and low-speed clutch disks or rings is a master-plate 30, supported by bolts 31 and adapted for slight lateral movements or movements endwise of the shaft 16, the said master-plate being pressed against by springs 32, encircling the bolts 31. Any suitable number of the bolts 31 and springs 32 will be provided in a circular series on the fly-wheel, as will be understood.

Attached to the shaft 12 is an eccentric 33, encircled by a strap 34, connected by a rod 35

with a piston 36, working in a cylinder 37, stationarily supported in any suitable manner, the chamber of the said cylinder being connected by a pipe 38 with a pressure-cylinder 39, mounted loosely on the shaft 16, and in which pressure-cylinder 39 is arranged an annular piston 40, which is in contact with a plate or disk 41, also loose on the shaft 16, so as not to rotate therewith. On the shaft 16 is a ring 42, and interposed between said ring and the plate or disk 41 is a thrust-bearing comprising balls 43, and a similar thrust-bearing, comprising balls 44, is interposed between the cylinder 39 and the gear-wheel 25. The ring 42 is in contact with the hub of the pinion 19 on the sleeve 17, and encircling the shaft 16 within the said sleeve 17 is a spiral spring 45, having a tendency to force said sleeve toward the piston 40 and cylinder 39, so as normally to prevent the clutch-hub 18 from exerting a clutching pressure against the clutch disks or rings inclosed within the fly-wheel 14. The spring 45 presses at its ends against rings 46 and 47, between which and other rings 48 and 49, encircling the shaft 16, are thrust-bearing balls 50.

The pipe 38 is preferably provided with a regulating needle-valve 51, which may be set as may be desired to permit of the escape of a small quantity of the pressure fluid from the said pipe 38 to provide for an automatic regulation of the pressure in the cylinder 39, and the said pipe 38 is also preferably connected by a pipe 52 with a manually-controllable relief-valve 53, held to its seat by a spring 54 within the sleeve 55, the said spring being under the control of a push-rod 56, provided with a button 57, on which the driver of an automobile may place his foot for the purpose of controlling the relief-valve 53. The rod 56 is preferably provided with notches 58 and 59, either of which or other similar notches may be engaged by the tooth of a pawl or catch 60, under the control of a spring 61. The air-pump is preferably provided with check and relief valves 62 63.

The operation of the invention is as follows: When there is little or no fluid-pressure within the cylinder 39, the spring 45 will hold the low-speed clutch disks or rings 26 and 27 out of frictional clutching engagement with each other and the springs 32 will likewise hold the high-speed clutch rings or disks out of clutching engagement with each other, so that the motor-shaft and the fly-wheel connected therewith can run free without imparting any motion to the driven shaft 16. When the motor or driving-shaft 12 attains a speed sufficient to cause the air or fluid pressure pump to raise the pressure in the cylinder 39 to a point sufficient to overcome the stress of the spring 45, the low-speed clutch-disks 26 27 will be forced into frictional clutching engagement with each other, thereby imparting rotary motion to the clutch-hub 18, and from the latter, through the sleeve

17, pinion 19, gear-ring 20, hub 21, grip-rollers 22, counter-shaft 23, pinion 24, and gear-wheel 25, to the driven shaft 16.

The pressure in the cylinder 39 may be regulated or governed by either of the relief or regulating valves 51 and 53, or by both of them, and when the pressure in the cylinder 39, as controlled by either or both of said valves, is sufficient to overcome the stress of the spring 45 and also the stress of the springs 32 the high-speed clutch disks or rings 29 and 29 will be forced into frictional clutching engagement with each other in such a manner as to impart motion to the hub 15, splined to the driven shaft 16, and thereby directly rotate the said shaft so that it will have the same speed of rotation as the fly-wheel and the motor or driving shaft, and when the high-speed clutch is thus directly rotating the driven shaft the low-speed gearing will idly overrun, owing to the fact that the spring-pressed rollers 22 will no longer be in gripping engagement with the hub 21, so that the low-speed gearing may run without interference with the high-speed mechanism, as fully set forth in United States Patent No. 766,551, hereinbefore referred to.

Owing to the fact that the friction disks or rings are inclosed in the fly-wheel casing, so that they may run in oil, there may be more or less slip or lost motion between them when the frictional gripping action first takes place or is changing, and thus the driven shaft may be started slowly without any sudden jerks, or the changes from low speed to high speed, or vice versa, may be smoothly effected without any such sudden jerks or jars as would occur if the changes of speed were to take place suddenly, the slipping or lost-motion action of the clutch rings or disks being possible in changing from high speed to low speed just the same as in starting or in changing from low speed to high speed.

It will be understood that the speeds at which the changes from low speed to high speed, or vice versa, are to occur may be predetermined by a suitable regulation of the relief or regulating valves 51 or 53, or may be effected at any time by suitable manipulation of the valve 53 by the driver or attendant, and that where the invention is applied to an automobile the regulating valve or valves may be set so that any desired speed of the motor may occur without necessarily setting the high-speed clutching device into action, and it will also be understood that such an adjustment of the relief or regulating valve or valves may be effected that no change in the driving mechanism will occur until the load or duty on the driven shaft 16, such as is determined by the road resistance and such as may be desired or predetermined changes, and when the road resistance or the duty on the said shaft 16 falls below a certain predetermined point the high-speed power-transmit-

ting mechanism will come into action and the low-speed mechanism will then run idly, as hereinbefore described.

While the preferred form of the invention is herein shown and described, the invention is not to be understood as being limited either to the details of construction herein shown or to the use of air as a pressure medium, or, in fact, to the use of a fluid-pressure medium at all for the purpose of effecting changes of speed, as instead of employing the pressure-cylinder 39 and its piston 40 for controlling the frictional clutching action of the multiple-disk clutch devices, such friction clutching action might be controlled either automatically or non-automatically by a wedge or similar device forced by the torque or the road resistance or otherwise between certain parts mounted on the driven shaft for the purpose of overcoming the stress of the springs 45 and 32 in effecting either the low-speed or the high-speed clutching action of the clutch-disks; also, instead of employing friction-clutch devices controlled from outside of the fly-wheel or clutch-casing or by fluid-pressure any other well-known or equivalent clutching devices might be used without departing from the essence of the invention.

Having thus described our invention, we claim and desire to secure by Letters Patent—

1. In a power-transmitting mechanism, the combination with a rotating driving part and a rotary part to be driven, of a rotating casing, high and low speed clutch devices within said casing, gearing mechanism through which power may be transmitted from one of said clutch devices to the rotary part to be driven, and means, outside of said casing, for effecting the clutching action of said clutch devices.

2. In a power-transmitting mechanism, the combination with a rotating driving part and a rotary part to be driven, of a rotating casing, clutch devices within said casing, gearing mechanism through which power may be transmitted from one of said clutch devices to the shaft or part to be driven, and means, outside of said casing and operated by fluid-pressure, for effecting the clutching action of the said clutch devices.

3. In a power-transmitting mechanism, the combination with a rotating driving part and a rotary part to be driven, of interposed high and low speed clutch devices, gearing mechanism, an inclosing rotary casing for the clutching members, and means, outside of said casing, for effecting the clutching operation of said members.

4. In a power-transmitting mechanism, the combination with a rotating driving part and a rotary part to be driven, of interposed high and low speed clutch devices, gearing mechanism, an inclosing rotary casing for the clutching members, and mechanically-operated means, outside of said casing, for effecting the clutching operation of said members.

5. In a power-transmitting mechanism adapted for use in automobiles, the combination with a rotating driving part and a rotary part to be driven, of a gearing and clutch mechanism, mechanically-operated fluid-pressure means for effecting the clutching action of the clutch device, and means for regulating the action of the fluid-pressure means, so that the said driving part or the said driven part may run at any desired speed for any predetermined load or road resistance. 75

6. In a power-transmitting mechanism adapted for use in automobiles, the combination with a rotating driving part and a rotary part to be driven, of a gearing and friction-clutch mechanism, mechanically-operated fluid-pressure means for effecting the clutching action of the friction-clutch device, and means for regulating the action of the fluid-pressure means, so that the said driving part 85 or the said driven part may run at any desired speed for any predetermined load or road resistance.

7. In a power-transmitting mechanism, the combination with a rotating driving part and a rotary part to be driven, of high and low speed clutch devices, gearing, means, operated by fluid pressure, for effecting the clutching action of said clutch devices, and springs, acting in opposition to the fluid-pressure means, for disengaging said clutch devices when the pressure is released. 90

8. In a power-transmitting mechanism, the combination with a rotating driving part and a rotary part to be driven, of high and low speed clutch devices, gearing, means, operated by fluid-pressure, for effecting the clutching action of said friction-clutch devices, and springs, acting in opposition to the fluid-pressure means, for disengaging said clutch 100 devices when the pressure is released.

9. In a power-transmitting mechanism, the combination with a rotating driving part and a rotary part to be driven, of an interposed friction-clutch mechanism, gearing, means, operated by fluid-pressure, for effecting the clutching action of said friction-clutch mechanism, means for regulating the action of the fluid-pressure means, and springs, acting in opposition to the fluid-pressure, for disengaging 110 the clutching parts when the pressure is released.

10. In a power-transmitting mechanism, the combination with a rotating driving part and a rotary part to be driven, of an interposed clutch mechanism, gearing, a rotating casing inclosing the clutching members, mechanically-operated fluid-pressure means, outside of said casing, for effecting the clutching action of said clutch mechanism, and springs 120 for effecting the unclutching of the clutch members.

11. In a power-transmitting mechanism, the combination with a rotating driving part and a rotary part to be driven, of an interposed 130

- friction-clutch mechanism, gearing mechanism, a rotating casing inclosing the clutching members, and mechanically-operated fluid-pressure means, outside of said casing, for effecting the clutching action of said friction-clutch mechanism, and springs, acting in opposition to the fluid-pressure, for disengaging the clutching parts when the pressure is released.
- 10 12. In a power-transmitting mechanism, the combination with a rotating driving part and a rotary part to be driven, of an interposed clutch mechanism, gearing, a casing inclosing the clutching members, mechanically-operated fluid-pressure means, outside of said casing, for effecting the clutching action of said clutch mechanism, means for regulating the action of the fluid-pressure means, and springs for disengaging the clutching members.
- 15 13. In a power-transmitting mechanism, the combination with a rotating driving part and a rotary part to be driven, of an interposed friction-clutch device, gearing mechanism, a casing inclosing the clutching members, mechanically-operated fluid-pressure means, outside of said casing, for effecting the clutching action of said friction-clutch device, means for regulating the action of the fluid-pressure means, and springs for disengaging the clutching members.
- 20 14. In a power-transmitting mechanism, the combination with a rotating driving part and a rotary part to be driven, of a high-speed clutch device directly connected with said part to be driven, a low-speed clutch device having a gearing connection with said part to be driven, means for preventing interference between the clutch mechanisms when either is operatively running, and means, operated by fluid-pressure, for effecting the clutching action of said clutch devices.
- 25 15. In a power-transmitting mechanism, the combination with a rotating driving part and a rotary part to be driven, of a high-speed friction-clutch device directly connected with said part to be driven, a low-speed friction-clutch device having a gearing connection with said part to be driven, means for preventing interference between the clutch mechanisms when either is operatively running, and means, operated by fluid-pressure, for effecting the clutching action of said friction-clutch devices.

In testimony whereof we affix our signatures in presence of two witnesses.
